Henry Dreyfuss, South Pasadena, Calif., assignor to Bell
Telephone Laboratories, Incorporated, New York, N.Y.,
a corporation of New York

Filed July 31, 1962, Ser. No. 71,117

Term of patent 14 years

(Cl. D26—14)

FIG. 1

FIG. 4

FIG. 2

FIG. 3

FIG. 1 is a perspective view of a coin telephone, showing my new design;

FIG. 2 is a front view, to a reduced scale;

FIG. 3 is a side view, to a reduced scale; and

FIG. 4 is a plan view, to a reduced scale.

The legible matter shown in broken lines is for illustrative purposes only. The dominant features of the design are shown in solid lines.

The hand set and connecting cord shown in dot-dash lines in FIG. 3 have been omitted from FIGS. 1, 2 and 4 for convenience in illustration. Portions of FIGS. 1 and 2 are diagonally lined to indicate transparency.

I claim:

The ornamental design for a coin telephone, as shown and described.
